(57) **CLAIM**

What is claimed is the ornamental design for a light fixture, as shown and described.

DESCRIPTION

FIG. 1 is a perspective view as viewed from above of the light fixture of our design;

FIG. 2 is a perspective view as viewed from below thereof;

FIG. 3 is a right hand side elevational view thereof;

FIG. 4 is a left hand side elevational view thereof;

FIG. 5 is a top plan view thereof;

FIG. 6 is a bottom plan view thereof;

FIG. 7 is a perspective view as viewed from above of another embodiment of the light fixture of our design;

FIG. 8 is a perspective view as viewed from below thereof;

FIG. 9 is a front elevational view thereof;

FIG. 10 is a rear elevational view thereof;

FIG. 11 is a top plan view thereof; and,

FIG. 12 is a bottom plan view thereof.

The dot-dash broken lines in the drawings are directed to environment, are for illustrative purposes and form no part of the claimed design.

The drawings contain a symbolic break. The portion between the break lines forms no part of the claimed design.

1 Claim, 12 Drawing Sheets

Related U.S. Application Data

a continuation of application No. 29/601,125, filed on Apr. 19, 2017, now abandoned, which is a division of application No. 15/299,168, filed on Oct. 20, 2016, now Pat. No. 10,215,380.
